(57) **CLAIM**

The ornamental design for a light guiding member, as shown and described.

DESCRIPTION

FIG. 1 is a front perspective view of a light guiding member showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view thereof;

FIG. 8 is a right side view thereof; and,

FIG. 9 is a cross-sectional view taken along the line of IX—IX of FIG. 3.

The oblique short lines in the drawings are intended to illustrate that the surface is translucent.
